UNITED STATES PATENT OFFICE.

STEPHEN LINCOLN TALLMAN, OF MIDDLETOWN, CONNECTICUT, ASSIGNOR
TO LUTHER SPENCER HULL, OF SAME PLACE.

DESIGN FOR A CAN-OPENER BODY.

SPECIFICATION forming part of Design No. 28,232, dated February 1, 1898.

Application filed May 3, 1897. Serial No. 634,949. Term of patent 7 years.

To all whom it may concern:

Be it known that I, STEPHEN LINCOLN TALLMAN, a citizen of the United States, residing at Middletown, in the county of Middlesex and State of Connecticut, have invented and produced a new and original Design for Can-Opener Bodies, of which the following is a specification, reference being had to the accompanying drawings, forming part thereof.

o Figure 1 is a plan view of a can-opener body, showing my design. Fig. 2 is an edge view of the same can-opener body.

As shown in the drawings, the leading or material feature of my design consists in the shape of the body of a can-opener.

The appearance of the body in plan is that of a strip having parallel sides for a portion of its length and curved sides for the remainder of its length, with a cone projecting from one end, the portion with the curved sides forming the handle of the can-opener.

Through the portion of the body that has the parallel straight sides there is an extended opening, with sides that are parallel with each other and with the sides of the body adjacent to the opening. 25

Looking edgewise this body shows as a thin strip of uniform thickness from one end to the other, with a tapering or conical part projecting downwardly and then forwardly from one end. This bent conical part is circular in cross-section and tapers gradually from the body to the point. 30

Having now described my design, what I claim, and desire to secure by Letters Patent, is—

The design for a can-opener body herein shown and described.

STEPHEN LINCOLN TALLMAN.
